US00D695316S

(12) **United States Design Patent**
Akana et al.

(10) **Patent No.:** US D695,316 S
(45) **Date of Patent:** ** Dec. 10, 2013

(54) **HOUSING FOR AN ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **John B. Ardisana, II**, San Francisco, CA (US); **Jeremy Bataillou**, San Francisco, CA (US); **John Oskar Ceideburg**, Santa Cruz, CA (US); **Daniel J. Coster**, San Francisco, CA (US); **Daniele De Iuliis**, San Francisco, CA (US); **Trent Do**, Milpitas, CA (US); **Colin Ely**, Cupertino, CA (US); **M. Evans Hankey**, San Francisco, CA (US); **Phillip M. Hobson**, Menlo Park, CA (US); **Julian Hoenig**, San Francisco, CA (US); **Richard P. Howarth**, San Francisco, CA (US); **Jonathan P. Ive**, San Francisco, CA (US); **Eric Steven Jol**, San Jose, CA (US); **Duncan Robert Kerr**, San Francisco, CA (US); **Shin Nishibori**, Kailua, HI (US); **Matthew Dean Rohrbach**, San Francisco, CA (US); **Fletcher Rothkopf**, Los Altos, CA (US); **Peter Russell-Clarke**, San Francisco, CA (US); **Anna-Katrina Shedletsky**, Mountain View, CA (US); **Mikael Silvanto**, San Francisco, CA (US); **Christopher J. Stringer**, Woodside, CA (US); **Hua Lee Tan**, Singapore (SG); **Eugene Antony Whang**, San Francisco, CA (US); **Rico Zörkendorfer**, San Francisco, CA (US)

(73) Assignee: **Apple Inc.**, Cupertino, CA (US)

(**) Term: **14 Years**

(21) Appl. No.: **29/452,805**

(22) Filed: **Apr. 22, 2013**

Related U.S. Application Data

(63) Continuation of application No. 29/431,557, filed on Sep. 7, 2012, now abandoned.

(57) **CLAIM**

The ornamental design for a housing for an electronic device, as shown and described.

DESCRIPTION

FIG. 1 is a top rear perspective view of a housing for an electronic device showing our new design;

FIG. 2 is a bottom front perspective view thereof;

FIG. 3 is a front view thereof;

FIG. 4 is a rear view thereof;

FIG. 5 is a top plan view thereof;

FIG. 6 is a bottom plan view thereof;

FIG. 7 is left side view thereof; and,

FIG. 8 is a right side view thereof.

1 Claim, 6 Drawing Sheets
